UNITED STATES PATENT OFFICE.

DANIEL T. SMITH, OF CINCINNATI, OHIO, ASSIGNOR OF ONE-HALF TO
FECHHEIMER, SCHEUER & CO., OF SAME PLACE.

SHOULDER-PAD.

SPECIFICATION forming part of Letters Patent No. 236,267, dated January 4, 1881.

Application filed June 3, 1880. (No model.)

To all whom it may concern:

Be it known that I, DANIEL T. SMITH, of Cincinnati, in the county of Hamilton and State of Ohio, have invented certain new and useful Improvements in Pads for Filling Out and Giving Shape to the Shoulders of Coats and Like Wearing-Apparel, of which the following is a specification.

It is well known that in the practice of tailoring, the shoulders of coats are commonly filled out between the cloth and the lining with cotton wadding or similar material in order to compensate for defects of person or to give a shapely fit. Heretofore this work has been left to the journeyman making up the coat, who, being supplied with a piece of wadding, would cut and mold it to suit his judgment and stitch it into place as the garment progressed toward completion. This has proven objectionable, not only on account of the superior skill and care required of the workman, the draft upon his time, and the fact that he rarely knows whom he is fitting, but also on account of the great waste of material. The mechanical difficulties in the way of getting the proper shape, and the almost impossibility of thus forming any two pads alike. Independent shoulder-pads of metal, or of a combination of metal and cloth, intended to be worn inside the coat between it and the vest, have also been made. They, too, have proven objectionable, not only because of their increased cost, but since, if worn detached from any garment, they must be adjusted every time the coat is put on, or, if permanently attached, are an obstacle to packing or laying away, and since there is a greater tendency of cloth to become threadbare or shiny over a hard surface than over one which is soft.

My invention consists in forming, as an article of manufacture, a shoulder-pad blank built up of cotton wadding or like material properly shaped and proportioned, and held together and protected by a covering of cheap cotton or other suitable binder, so that it may be delivered to the journeyman ready to be applied and fixed in position. These blanks will be sent out in pairs by the cutter or fitter when sending goods to the workmen to be made up, and I propose to manufacture them of such numbers or sizes, and of such shapes and styles,

that a pair may always be selected most appropriate to the person being fitted, or to the class of goods being made.

In order to enable others to construct and use my invention, I will proceed to describe the best mode known to me of carrying it into effect, reference being had to the accompanying drawings, in which—

Figure 1 is a perspective view of a blank prepared according to my invention. Fig. 2 is a bottom-plan view, the cover or binder being removed, and Fig. 3 is an enlarged section on the line xx of Fig. 2.

I cut or stamp out, from cotton wadding or whatever stock may be used, a series of diminishing lifts, A B C D, of substantially the outline shown—that is, with one side, a , so slightly curved as to approximate a straight line, and the other side, b , quite sharply curved, the general form being that of a segment. I also cut from cheap cotton cloth two covering-pieces or binders, E F, of the size and shape of the largest of the lifts, and from canvas three stiffening-pieces, $c d e$, shaped like but smaller than the second lift of wadding, and, like these lifts, they may be, and preferably are, of diminishing sizes. The component parts of the blank having been prepared, I take one of the covering-pieces, E, and upon it place the largest or top piece of wadding, so that its edge may coincide throughout with that of the cover-piece. Upon this wadding is next placed one of the larger stiffening-pieces, c , so that its shorter edge may coincide with the edge a and its longer edge be centered with the edge b of the wadding, and, in turn, the stiffening-piece is covered with the second lift of wadding, which is likewise matched with one underlying edge and centered with respect to the other. In this manner the blank is built up alternately of diminishing lifts of wadding and interposed stiffening-pieces, the smallest stiffening-piece being laid last and overlaid with the smallest lift, when the bottom cover-piece, F, is placed in position and the whole structure secured together by basting-stitches passing through and through, and the blank is complete. The shorter edge of the finished blank is square and of considerable thickness throughout nearly all its length, the thickest portion of the blank being along the center of this

edge and over the area covered by the smallest lift of wadding. Between this lift and the extreme outer edge, *b*, the blank gradually falls away to a thickness measured by the 5 single lift of wadding and the two cover-pieces at that edge.

In applying the blank to a garment the shorter and thicker edge is placed next to the seam which unites the arm to the body, so as 10 to form a square shoulder. In use the smaller lift will be undermost and be overlapped by each succeeding lift; therefore there will be no breaks on the exterior to mar the symmetry.

15 The blank may be stitched over a block, so as to have at the outset the approximate shape of a shoulder; but I prefer to form it flat, as shown, that it may have more stiffness and resiliency. It may be formed of cotton wadding 20 manipulated into proper shape and held together by cover-pieces and through-and-through stitches, though this I do not consider so cheap or reliable. It may also, as already stated, assume modified sizes or forms to suit varying 25 conditions or contingencies. Such modifications can readily be produced by slight and obvious changes in the number, shape, or arrangement of the lifts.

It is evident that with blanks of the construction described less special skill will be required in the journeyman, and the execution 30

of his work greatly facilitated both as to time and as to labor. Waste, also, in this particular feature can be reduced to a minimum, since the stock for the blanks can be cut to the 35 greatest advantage and all waste scraps worked into them.

I claim as my invention—

1. A shoulder-pad blank of essentially the form shown and set forth, of tapering thickness from its outer edge, composed of soft and flexible material, and adapted to be inserted bodily and permanently secured in place in the process of making up the garment, substantially as described. 40

2. A shoulder-pad blank shaped substantially as described, formed of cotton wadding with covering-pieces of cloth, held in shape by stitches through and through the covers and wadding, and adapted to be inserted bodily 45 and permanently secured in place in the process of making up the garment.

3. The shoulder-pad blank built up of diminishing lifts of cotton wadding, with interposed stiffening-pieces and a suitable cover, 50 and united by stitches passing through, substantially as described.

DAN. T. SMITH.
